WALL PLATE FOR HOSPITAL GAS OR THE LIKE

Chester C. Perry, Grover, Mo., assignor to Stile-Craft
Manufacturers, Inc., St. Louis, Mo.

Continuation-in-part of abandoned design application Ser.
No. 24,922, Sept. 10, 1970. This application Aug. 11,
1971, Ser. No. 171,035

Term of patent 14 years

Int. Cl. D8—09

U.S. Cl. D8—188

FIG. 5

FIG. 3

FIG. 1

FIG. 4

FIG. 2

FIG. 1 is a front elevational view of a wall plate showing my new design;

FIG. 2 is a cross section taken on line 2—2 of FIG. 1;

FIG. 3 is a cross section taken on line 3—3 of FIG. 1;

FIG. 4 is a side elevational view thereof;

FIG. 5 is a rear elevational view thereof;

FIG. 6 is a front elevational view of a modification thereof;

FIG. 7 is a cross section taken on line 7—7 of FIG. 6;

FIG. 8 is a cross section taken on line 8—8 of FIG. 6;

FIG. 9 is a side elevational view of the wall plate in FIG. 6, and

FIG. 10 is a rear elevational view of the wall plate of FIG. 6.

This application is a continuation-in-part of application Ser. No. D-24922, filed Sept. 10, 1970, now abandoned.

I claim:

The design for a wall plate for hospital gas or the like, substantially as shown and described.
